UNITED STATES PATENT OFFICE.

ALBERT D. PENTZ, OF ELIZABETH, NEW JERSEY, ASSIGNOR TO THE SINGER
MANUFACTURING COMPANY OF NEW JERSEY.

TENSION DEVICE FOR SEWING-MACHINES.

SPECIFICATION forming part of Letters Patent No. 319,744, dated June 9, 1885.

Application filed February 18, 1885. (No model.)

To all whom it may concern:

Be it known that I, ALBERT D. PENTZ, a citizen of the United States, residing at Elizabeth, in the county of Union and State of New Jersey, have invented certain new and useful Improvements in Tension Devices for Sewing-Machines, of which the following is a specification, reference being had therein to the accompanying drawings.

10 The object of my invention is to provide a simple and effective tension device which is more particularly adapted to be applied to the cap or face plate of a sewing-machine, and to be regulated by a pointed adjusting-screw placed on the top of said plate.

15 In carrying my invention into effect I employ a lever-spring similar to that shown by Patent No. 214,513, to L. B. Miller, but provided at its lower end with an offset portion which extends outward through the face-plate, so that it may bear on the outer face of a tension-block pivoted to said face-plate, the adjacent faces of the said block and the offset portion of said lever-spring forming 25 the friction-surfaces between which the thread passes.

20 In the accompanying drawings, Figure 1 is a face view of the cap or face plate of a sewing-machine with my invention applied thereto, and Fig. 2 is a section of the same and of 30 a portion of the contiguous part of the bracket-arm.

25 A indicates the cap or face plate of a sewing-machine in which the needle and presser bars have vertical bearings, said face-plate having a slot, *a*, through which the take-up lever *B* projects, as is usual with many sewing-machines.

35 C is a lever-spring loosely attached by a screw, *c*, to the inside of the face-plate, said lever-spring having a bent upper portion, against which impinges the pointed end of a regulating-screw, *D*.

40 At the lower end of the lever-spring *C* is a bent or offset portion, *c'*, projecting outward through the face-plate and provided with a slotted thread-hole, *c''*, and in the bend just above the offset portion *c'* is formed a thread-

guiding notch, *c''*. One side of the lower end of the portion *c'* is turned outward, as at *c''*, 50 forming a lip to facilitate threading. The inner side of the face-plate is preferably provided with a small projection, *a'*, forming the fulcrum of the lever-spring *C*.

55 E is a pivoted tension-block secured in the slot or recess in the face-plate through which the lever-spring passes, the outer face of said block projecting slightly beyond or outside of the outer surface of the face-plate, so that the lower offset portion of the lever-spring 60 can have a full bearing against the said block, the latter being self-adjusting on its pivot to accommodate varying positions of the spring-lever, and thus keep the friction-surfaces for the thread afforded by the adjacent faces of 65 said block and the offset portion of said lever parallel.

70 My tension device is threaded by drawing the thread (indicated by dotted line *b*) beneath the outwardly-projecting lip *c''* into the thread-hole *c''* and notch *c''*, whence it passes upward to the take-up lever and then downward to the needle. The tension is varied by means of the pointed regulating-screw *D*, as in the device shown by the patent to Miller, 75 hereinbefore referred to.

75 I do not wish to be understood as limiting my invention to the particular location on the machine in which it is herein shown, as it is obvious that it may be placed in any 80 convenient position on the machine, as circumstances may require.

I claim as my invention—

85 1. In a sewing-machine tension device, the combination, with a lever-spring having a bent end, as shown, and a regulating-screw movable lengthwise of the said lever-spring and bearing against the said bent end, of a pivoted tension-block, against which the opposite end of said lever-spring bears, substantially as set forth.

90 2. The combination, with the cap or face plate of a sewing-machine, of a lever-spring secured inside thereof and having an offset outwardly-projecting portion, a pivoted tension-block, also attached to said face-plate,

and a regulating-screw at the top of said face-plate bearing against the upper end of said lever-spring, substantially as set forth.

3. The combination, with the cap or face plate A, of the lever-spring C, having offset portion c' , slotted thread-hole c^2 , guiding-notch c^3 , and outwardly-projecting lip c^4 , the pivoted tension-block E, and the regulating-screw D, substantially as set forth.

In testimony whereof I affix my signature to
in presence of two witnesses.

ALBERT D. PENTZ.
